SWING SEAT OR THE LIKE

Howard B. Kimble, 3100 Arrowwood Drive,
Raleigh, N.C. 27604

Filed Mar. 10, 1971, Ser. No. 123,128

Term of patent 14 years

Int. Cl. D21—02

U.S. Cl. D34—5 M

fig. 3

fig. 2

fig. 1

fig. 4

fig. 5

fig. 6

fig. 7

FIG. 1 is a perspective of a swing seat or the like showing my new design;

FIG. 2 is a perspective of a slightly modified version of such design;

FIG. 3 is a slightly further modified perspective of the same;

FIG. 4 is a top plan view of the design shown in FIG. 1;

FIG. 5 is a bottom plan view of the same;

FIG. 6 is a side elevational view of such design; and

FIG. 7 is an end elevational view of the same.

I claim:

The ornamental design for a swing seat or the like, as shown.
